UNITED STATES PATENT OFFICE

FRANK KUCHERA, OF TACOMA, WASHINGTON

SWING

Application filed September 17, 1928. Serial No. 306,501.

My invention pertains to swings commonly used for recreation and pleasure. It is more particularly designed to be used in private lawns and for family use where an easily operated, restful swing is desired. It will also be found useful in public parks, in playgrounds and other similar places.

One of the objects of my invention is to provide a swing that is partly automatic and can thus be easily operated without the strenuous use of the feet and limbs as is required by swings now in general use. It has the further object of providing a swing in which a gentle, moderate swinging motion can be obtained while the occupant is sitting relaxed, or lying at rest; a swing in which a child or an invalid can swing themselves with but little physical effort.

I attain these objects by means of the mechanism illustrated in the accompanying drawings, in which—

Fig. 1 is a top view of my invention as set up on the ground; Fig. 2 is a front view of Fig. 1, and Fig. 3 is a top view of Fig. 2; Fig. 4 is a side view of the top part of my invention as designed to be hung from a ceiling or other overhead support; Fig. 5 shows a side, end and top view of the pulleys over which the swing's operating cord is run; Fig. 6 is a side view of my invention with the automatic counterweights suspended on cords at its sides; Fig. 7 is a partial front view of Fig. 6 showing how the counterweights' cords are attached at the top of the swing; Fig. 8 is a top view of the bottom part of Fig. 6 from the line 8—8; Fig. 9 is an enlarged top view of the guide pulleys of the counterweight cords near the ground; and Fig. 10 is a side and top view of the slotted members on the sides of the swing seat to allow a slight rocking motion.

Similar characters refer to similar parts in the several views.

My invention is supported on a stout form of frame, preferably of wood, with upright supports 1 set on a ground frame of sills 2 and cross tie members 3. The swing pivot beams 4 and the cross tie members 5 at the top make the supporting frame complete,

proper braces being added as shown to make the same rigid.

The swing seat 6 may be of any suitable form or size desired. It may be of a length to allow an occupant to lie down, the frame being widened to receive it. The seat is hung between the bars 7 which are pivotally hung by means of a tubular bar 8 with its ends extended to rest in the bearings 9 of the beams 4. The seat ends are attached to the bars 7 by suitable means, preferably by a tubular bar 10, passing through the ends of the seat and beneath the seat proper. Near the top of the seat ends the bars 7 are attached to slotted members 11, more fully shown in Fig. 10. These slotted members allow a slight rocking motion to the seat and adjust it to the motion of the swinging seat and to the comfort of the occupant.

The swinging bars 7 are extended above the pivotal bearings to support a tubular bar 12 on which two counterweights 13 are mounted or suspended. These are of sufficient weight to almost balance the weight of the swinging seat below the pivot bar 8. By these counterweights the swing is made to swing more easily when in use. The swing is operated by means of a cord 14 centrally attached to the bar 12. This cord passes downwardly to the rear and under a pulley 15, then forward over a second pulley 16 and down in front of the swing seat. A pull on the cord will impart a forward movement to the swing seat, and any one occupying the seat can thus swing himself forward without other effort. The weight of the occupant will swing the seat backward when another pull on the cord will impel the seat further forward. In this way a moderate and restful swinging movement forward and back without further exercise of other parts of the body, is attained.

It will be observed as a well known fact that in operating a swing the greatest effort is required in the forward movement. The counterweights 13 and the cord 14 passing over the pulleys 15 and 16 are designed to secure this forward movement. By vigorous pulling on the cord 14, the seat can be made to swing quite high, though my invention is

designed for more restful exercise. A moderate swinging movement can be secured with slight effort.

In Fig. 4 is shown how the frame members 4 and 5 can be hung from a ceiling or other overhead support by means of suspension bars 17. By this means my invention can be put up in a summer porch, in a pavilion or in other places where an overhead support is available. The invention will be useful in many such places.

A supplemental manner of using the counterweights is shown in Figs. 6, 7 and 8. In this method the tubular bar 12 is made some longer so the ends will extend over and outside the supporting frame. The counterweights are then hung, one from each end of the bar 12 by means of a small stout chain or wire cable 18, the weights being concealed in pits below the surface of the ground as shown at 19. In some instances, this method of attaching the counterweights may be considered preferable. It will be observed the cables near the ground are confined between two pulleys 20 so the weights will act only in vertical lines.

It will be observed that the novel idea of my invention is in the counterweights fixed on or attached to the swinging bars above their pivotal bearings to partially balance the weight of the swinging seat. By this means the object is attained of securing or providing a swing in which a moderate, restful swinging motion can be secured with easy effort by the occupant. It is thus a new and useful means by which the objects and purposes set forth are obtained.

It is to be further observed that I do not limit myself to proportions, dimensions or materials, but reserve the right to vary the same as circumstances and conditions may require.

It is to be further observed that I reserve the right to use my invention without the use of the operating pull cord 14 since the attached counterweights will so equip the ordinary form of swing to be operated more easily than as now constructed. They alone will be a marked improvement to any swing hung with stiff swinging bars.

Having described my invention, I claim:

The combination in a swing of the class indicated, of a supporting frame, seat supporting bars extending above their pivotal bearings in said frame, the seat of said swing partly balanced by counterweights suspended from the top ends of said extended bars, and said counterweights confined within pits beneath the surface of the ground with guide pulleys for said cables whereby said counterweights will be made to reciprocate vertically within said pits, as described and shown and for the purposes set forth.
